UNITED STATES PATENT OFFICE.

CALVIN HENRY SIMMONS, OF MUNFORD, ALABAMA.

PEA-THRASHER AND COTTON-OPENER.

SPECIFICATION forming part of Letters Patent No. 293,098, dated February 5, 1884.

Application filed July 31, 1883. (No model.)

To all whom it may concern:

Be it known that I, CALVIN H. SIMMONS, of Munford, in the county of Talladega and State of Alabama, have invented a new and 5 Improved Pea-Thrasher and Cotton-Opener, of which the following is a full, clear, and exact description.

My invention is for thrashing peas and other grain, and also for beating, opening, and 10 cleaning seed-cotton to prepare it for the gin by removing dirt, gravel, nails, and other matters injurious to the lint and damaging to the gin, besides being dangerous on account of causing the gin to strike fire, all as hereinafter fully described.

Reference is to be had to the accompanying drawings, forming part of this specification, in which similar letters of reference indicate corresponding parts in all the figures.

20 Figure 1 is partly a side elevation and partly a sectional elevation of my improved machine, and Fig. 2 is a sectional elevation of the machine on the line $x-x$ of Fig. 1.

I provide a thrashing and beating device 25 consisting of the perforated sheet-metal or woven-wire concave a , having spikes or teeth b , and the revolving shaft c , having other teeth, d , which teeth I prefer to bend or curve reversely to each other, as shown in Fig. 2, 30 to hold the straw, lint, and other matters and break or open them more effectually, and particularly to collect and hold the vines above and away from the perforated bottom and walls of the case, keeping the perforations 35 open, and thereby causing a better separation of the peas from the vines. Into this thrasher I supply the pea-vines and other grain to be thrashed directly through the feed-opening e in the side of the case, which consists of a 40 vertical extension, f , of the concave above the beater to the extent of two or three times the diameter of the beater, which extension is continuous over the top, and is not perforated.

When the machine is to be used for beating 45 and opening seed-cotton, I prefer to apply a trough, h , to the beater-case, said trough being perforated or reticulated, and containing a revolving shaft, i , with beater-arms j , preferably set spirally, and increasing in length 50 toward the inner end of trough h . By the arms j the cotton, which is fed into end opening, h' , of the trough, is to be first treated to

a slight beating process to expel the sticks and other refuse matters, after which it passes through spout k into the concave a , to be still 55 further and more powerfully beaten, if necessary, opened, and cleaned of the gravel, nails, dirt, trash, and the like. The heavy matters escape through the openings or perforations of the concave, while the lint is drawn upward 60 in case f to the fan-blower l , located at one end of case f , by the suction of said fan, which also assists to draw the cotton into the concave, and it discharges the lint through the spout m .

When peas and other grain are to be thrashed, the grains are to escape from the concave through the perforations of the same, while some broken and partly-thrashed stems and heads containing grain, and being too 70 heavy to be discharged along with the straw, pods, and other light matters by the fan, will escape through the opening at o through one end of the concave provided for a passage for them.

75 For operating the machine, the beater-shaft c will have the main driving-belt applied to a pulley, p , on it, and said shaft will have a cone-pulley, g , to drive the fan by another cone-pulley, s , to vary the speed as required; 80 and when the cotton-beater i, j is employed it will be driven by a belt, t , from a pulley on the beater-shaft c .

The machine is to be constructed in different sizes, and is designed to work lightly and 85 not very fast, to cause a kind of grinding action rather than the common high-speed thrashing motion, especially when used for treating cotton, so that it may be worked to advantage by hand-power, that may be applied 90 by a hand-crank to be fitted to the square extension u of the shaft c . I also propose to employ the machine, in connection with mowing and reaping machines, for thrashing peas at the same time that they are harvested, by 95 attaching it to the machine and gearing it so that the grain will be delivered directly to it from the reaper by an elevator or other approved means, and a suitable receptacle will be provided for the grain to fall into from the 100 concave a .

I propose to construct the concave a so that teeth b may be added and removed, as may be required for different kinds of grain or for

thrashing cotton, which may be treated better with less teeth, while peas may require more.

Having thus described my invention, what I claim as new, and desire to secure by Letters

5 Patent, is—

1. An end-rounded oblong case, *f*, provided with perforations and curved teeth *b* on the bottom, and an opening, *o*, at one end, near the bottom, in combination with reversely-curved 10 teeth *d*, arranged on a rotary shaft, to intermesh with teeth *b*, and a suction-fan communicating with said case near the top of the latter, as described.

2. The combination, with a bottom-perforated oblong case, *f*, of the connected preparatory beater *h i j*, the bottom beaters, *b d*, and a suction-fan connecting with the upper part of the case, whereby the fan will feed the material from the preparatory to the main beater, and then remove the lighter particles, as de- 20 scribed.

CALVIN H. SIMMONS.
